(57) **CLAIM**

The ornamental design for a wrench socket as shown and described.

DESCRIPTION

FIG. 1 is a front perspective view of a wrench socket, in accordance with the present invention;

FIG. 2 is a back perspective view of the wrench socket of FIG. 1;

FIG. 3 is a front view thereof;

FIG. 4 is a back view thereof;

FIG. 5 is a right side view thereof;

FIG. 6 is a left side view thereof;

FIG. 7 is a top plan view thereof; and,

FIG. 8 is a bottom plan view thereof.

The broken lines shown in the drawings illustrate aspects of the wrench socket in which the design is embodied that form no part of claimed design.

1 Claim, 5 Drawing Sheets
